FORCE INDICATING COMPONENT FOR MUSCLE EXERCISING AND TESTING APPARATUS

William E. Berne, Columbia, S.C., assignor to La Berne Manufacturing Company, Inc., Columbia, S.C., a corporation of South Carolina

Filed Nov. 6, 1967, Ser. No. 9,298

Term of patent 14 years

(Cl. D52—6)

FIG. 1

FIG. 2

FIG. 3

FIG. 4

FIGURE 1 is a perspective view of a force indicating component for muscle exercising and testing apparatus embodying my new design;

FIGURE 2 is an elevational view thereof;

FIGURE 3 is a top plan view thereof; and

FIGURE 4 is an end elevational view thereof.

I claim:

The ornamental design for a force indicating component for muscle exercising and testing apparatus, substantially as shown.
